UNITED STATES PATENT OFFICE.

WALTER A. SCOTT, OF DULUTH, MINNESOTA.

PROCESS FOR TREATING DURUM OR MACARONI WHEAT.

1,071,184.

Specification of Letters Patent.

Patented Aug. 26, 1913.

No Drawing.

Application filed May 5, 1910. Serial No. 559,515.

To all whom it may concern:

Be it known that I, WALTER A. SCOTT, a citizen of the United States, residing at Duluth, in the county of St. Louis and State of Minnesota, have invented a new and useful Process for Treating Durum or Macaroni Wheat, of which the following is a full, clear, concise, and exact description.

My invention relates to a process of treating durum or macaroni wheat for milling.

Durum wheat, sometimes known as macaroni wheat, as is well known, can be grown in climates in which, on account of deficient moisture, the ordinary spring wheat cannot be grown to advantage. Within the past decade durum wheat has been grown to a considerable extent in the United States, particularly the northwestern parts thereof. Durum wheat has for many years been extensively cultivated in some of the foreign countries.

It is the object of the present invention to improve the color, quality and bread-making characteristics of durum wheat.

The process of my invention may be conducted as follows:

Example 1: The wheat is first thoroughly washed to remove all dust, light seeds, and all foreign material. The dirty water is then separated as completely as possible from the wheat by some of the well known methods such as by passing the same over wire screens or by means of the usual centrifugal machines. The clean, washed wheat is then thoroughly wetted with water of a temperature of about 100 to 110 degrees Fahrenheit. The moisture should permeate the interior of the berry. The wheat is then placed in jute sacks, the sacks being placed in separated position, where it is allowed to remain for from twenty-four to thirty-six hours. A slight temporary rise in temperature may take place. The temperature at the end of this period varies from 80 to 90 degrees according to the external temperature. The wheat is then dried to about 12 per cent. moisture. It is then tempered, being wetted slightly with water at about 90 degrees Fahrenheit, and allowed to stand in bins for some twelve hours, during which time a rise in temperature may or may not take place, after which it is dried, if necessary, and milled by the usual methods.

Example 2: The wheat washed as in Example 1 is heated in a kiln to about 110 de-

grees Fahrenheit. It is then wetted by sprinkling with water of about the same temperature, the wheat being spread for this purpose in thin (one-half inch) layers. The wheat is permeated with moisture throughout the interior of the berry. A slight circulation of air is maintained in the kiln. The temperature is held as nearly constant as practicable, and the wetting repeated as often as is necessary to keep the wheat in a thoroughly moist condition. About eight hours of this treatment usually suffices for proper conditioning of the wheat. It is then dried, rewetted slightly, and allowed to stand in the bin, to temper it as above described.

The two examples above described sufficiently set forth the features of my process so that the same may be practised by the art. The process may be otherwise practised and by the utilization of any suitable machinery and apparatus, the important characteristic of the process being the treatment which gives the necessary balance, above outlined, of the three factors, heat, air and moisture. In the first example the jute sacks, while allowing a slight circulation of air, still retain the major part of the heat and the moisture. The wheat is thus subjected to the influence of the three factors, heat, air and moisture. In the second example the spreading of the wheat in thin layers permits ready access of the air, and the wetting, repeated from time to time, maintains the wheat in the thoroughly moist condition and during this period the wheat is subjected continuously to the action of heat.

It is to be noted that the wheat should be permeated with added moisture substantially throughout the berry. Tests of the wheat show that the best results are obtained when from 20 to 25 per cent. of moisture is present during the action of the heat, air and moisture, but the process can be practised successfully with a higher or a lower percentage of moisture.

Tests show that the best results are secured with an initial temperature of 100 to 110 degrees Fahrenheit, although successful results can be obtained by a somewhat higher temperature as well as by a somewhat lower temperature. The air should have free access during the process, but it should not be in such quantity or of such low humidity as to materially lower the

temperature or the moisture content of the berries below that above indicated if best results are to be secured. The period of time for the action of the moisture, heat and air 5 may be varied within reasonable limits by the proper balance of the several factors. Care is to be taken that the period is not prolonged to a stage where germination or 10 objectionable moldiness occurs if best results are to be secured. Of course, the period must not be so short that favorable results are sacrificed. The periods above mentioned in the specific examples will be found to give good results.

15 It is manifest that the process may be practised in various ways without departing from the spirit and scope of my invention, so long as the conditioning of the wheat is secured through the proper balance of the 20 three factors, heat, air and moisture, throughout the period of treatment, in substantially the manner above set forth.

During the conditioning of the grain I find that the kernels change from a flinty to 25 a starchy condition. Tests indicate that the bran of the grain is rendered by the process tough and leathery, and the same is true of the walls of the cells which contain the starch granules and which are distributed 30 throughout the mass of the wheat kernel, as well as the cell walls of the germ. The rendering of the bran and the cellular walls tough and leathery, instead of remaining dry and brittle, prevents these portions of 35 the kernel from being ground into fine particles during the milling process, and in consequence these portions may be readily removed by rolling, bolting, etc., in the usual process of milling.

40 My improved process, moreover, serves to induce oxidation and crystallization of the oil distributed throughout certain portions of the wheat kernel. The oil is thus lightened in color to improve the color of the 45 flour. Tests show that the oil extracted from the wheat berry treated in accordance with my process is much lighter in color than the oil extracted from the untreated berry on account of the partial crystallization. The iodin absorption number of the 50 oil is decreased by my process, the average decrease of a large number of specimens being 10 per cent. The percentage of the free fatty acids is increased in value by 55 to 25 per cent. The viscosity of the oil is materially increased. The treatment by my process, moreover, renders the gluten extremely elastic, thus adding substantially to the bread-making quality of the flour.

60 The treated wheat may be milled immediately or may be stored as customary for subsequent milling. If stored for any length of time it may be desirable to retemper the wheat in the usual manner before milling.

65 In making flour the treated wheat berry

is ground and the flour separated from the germ and bran by the usual milling process. The flour is light in color and equal to the best spring wheat flour. Tests show that the flour of durum wheat treated in accordance with my invention possesses substantially as ideal bread-making qualities as the best spring wheat flour.

70 Durum wheat, as is well known, is considered inferior for bread-making purposes and 75 sells upon the market for substantially less than the best or standard spring wheat. By my invention I can improve the quality of durum wheat to such an extent that it is the equal of the best or standard spring 80 wheat, in bread-making quality.

The product resulting from my process is a durum wheat berry having the cellulosic components rendered tough and leathery, the oil partially oxidized and crystallized 85 and lightened in color, and the gluten rendered more elastic as described herein.

Having thus described my invention and the best manner now known to me of practising the same, I declare that I claim the 90 following:

1. The process of preparing wheat for milling which consists in subjecting the wheat to moisture to permeate the berry substantially throughout and the action of 95 heat and air.

2. The herein described process which consists in subjecting durum wheat, permeated throughout the berry with added moisture, to the action of air and heat, substantially as described.

3. The herein described process of treating durum wheat which consists in permeating the berry with moisture throughout and subjecting the same to the action of air 105 and heat to render the cellulosic components tough and leathery, to partially oxidize and crystallize and lighten the color of the oil, and to render the gluten more elastic, substantially as described.

4. The herein described process of treating durum wheat which consists in subjecting the grain to the action of moisture and heat, the heat being sufficient to raise the temperature of the grain to about 100 to 115 110 degrees Fahrenheit and the moisture applied until the grain is permeated throughout, and subjecting the moistened and heated grain to the action of air, whereby, due to the action of the moisture, heat and air, the 120 cellulosic components of the grain are rendered tough and leathery, the oil partially oxidized and crystallized and lightened in color, and the gluten rendered more elastic.

5. The herein described product which 125 consists of a durum wheat berry having the cellulosic components thereof rendered tough and leathery, the oil partially oxidized and crystallized and lightened in color, the gluten rendered more elastic, and the inte- 130

rior of the berry starchy instead of flinty, substantially as described.

6. The process of preparing wheat for milling, comprising heating the wheat, subjecting the same while heated to moisture for a time sufficient to thoroughly permeate the wheat berries, and then drying said wheat to an extent sufficient for milling.

7. The process of preparing wheat for milling, comprising heating the wheat, subjecting the same to moisture while heated to

thoroughly permeate the wheat berries and subjecting said wheat while heated and moistened to a current of heated air for several hours.

15

In witness whereof, I have hereunto subscribed my name in the presence of two witnesses.

WALTER A. SCOTT.
